Patented Dec. 5, 1922.

UNITED STATES PATENT OFFICE.

CHARLES MEUNIER, OF GREAT NECK, NEW YORK.

GUTTER HANGER.

Application filed June 10, 1921. Serial No. 476,437.

To all whom it may concern:

Be it known that I, CHARLES MEUNIER, a citizen of the United States, and resident of Great Neck, in the county of Nassau, Long Island, and State of New York, have invented a new and Improved Gutter Hanger, of which the following is a full, clear, and exact description.

My invention relates to a hanger and aims 10 to provide certain new and useful improvements in connection with a device of this character, and more particularly a device such as is associated with gutters or leaders.

In connection with hangers of the type 15 specified, it is well appreciated that considerable difficulty has been experienced in providing a hanger which would properly support a leader or gutter, be capable of an adjustment, and which would also permit of 20 its being produced at a nominal figure.

Furthermore, difficulty has been experienced in the application of a hanger of the type specified to a leader, in that a relatively great amount of time has been necessary in 25 properly associating the hanger with the leader or gutter.

Thus it is an object of my present invention to provide a hanger primarily intended for supporting a gutter, and by means of 30 which a supporting element will be provided capable of ready association with the member to be supported.

A further object of my invention is the construction of a device of the character 35 specified which shall be capable of being manufactured at a nominal figure, and which will provide all of the adjustments necessary to the proper hanging of the gutter.

40 Other objects of my invention will become apparent in the annexed specification, taken in connection with the drawings which latter illustrate one practical embodiment of the same, and in which;

45 Figure 1 is an end view of the gutter or leader and showing the same supported by means of my improved type of hanger.

Figure 2 is a plan view thereof, and

50 Figure 3 is a fragmentary perspective view of one of the details of construction of a slightly different form of hanger.

55 Referring now more particularly to the figures it will be seen that the reference numeral 5 indicates the gutter or leader which is supported by my improved type of hanger, this in turn being suspended from

the eaves of a roof or other portion, by means of any conventional type of strap 7 preferably provided with a vertical series of openings 8, so as to support the hanger by 60 means of a bolt 9 extending through one of these openings.

Referring now to the construction of the hanger it will be seen that the same is preferably formed of a flexible material such as 65 brass, or any other metal may be utilized to advantage in this connection. The said hanger is conveniently formed of a single body providing a curved portion 10 having one of its ends terminating in a hook 11, its 70 opposite end being curved as at 12 to provide a recess capable of accommodating the flange 13 of a gutter, if this type of leader is utilized, a secondary part of said hanger comprising a portion adapted to extend 75 above and transversely of the gutter 5.

This latter portion is preferably twisted as at 14 for the purpose of securing greater 80 rigidity, and also to provide a part capable of being struck out as at 15 to accommodate the end of the strap 7, and lie against the same.

The outer end of the secondary portion 85 of the hanger terminates at a point adjacent the hook 11, and preferably is extended in the form of a prong 16 adapted to project through an opening forming a part of the hook portion 11. Thus the workman applying the leader 5 may primarily secure the straps 7 in position, subsequent to which the hanger may be associated with the straps. The leader or gutter 5 may be applied to 90 the hangers by simply detaching the hook 11 from the prong 15 and moving the thus freed ends of the hanger apart and sliding 95 the leader into that space thus provided.

This is also permitted by virtue of the resiliency imparted to the whole hanger by the curved portion 12 and immediately the flange 13 of the leader rests in its proper 100 position within this curved portion, the hook 11 may be reattached to the flange 13 and a vertical adjustment of the whole resorted to by means of the openings 8 and bolt 9, if this is found necessary.

105 The prong 16 and opening of the hook may be dispensed with if this is desired by simply striking the outer end of the transversely extending portion, upwardly, as at 17 in Figure 3, this upwardly bent portion 110 co-operating with the inner face of the hook 11, the resiliency and natural tendency of

the parts to align serving in this instance to retain the whole in proper position.

Thus it will be appreciated that the objects of this invention are accomplished in that a commercially feasible hanger is provided in which the parts will readily conform to the leader, utilized in such a manner that the leader is properly held against movement, this being effected in an extremely short period of time, in that it is only necessary to separate the ends of the hanger and to slip the leader between the same, subsequent to which these ends may be reapplied to each other.

15 Obviously numerous modifications of structure might readily be resorted to with-

out in the least departing from the spirit of my invention, which I claim as:

A gutter hanger including in combination a body adapted to extend across a gutter, 20 means for attaching said gutter to said body, an outstruck portion formed in said body at a point substantially intermediate its extremities, the inner face of said outstruck portion extending substantially parallel to the major part of the body, a strap 25 adapted to lie flush against the inner face of said outstruck portion, and means extending through said strap and body for retaining said parts in applied position with respect to each other.

CHARLES MEUNIER.
